UNITED STATES PATENT OFFICE.

MORGAN DONNE, OF LONDON, ENGLAND.

TYPE-WRITING MACHINE.

SPECIFICATION forming part of Letters Patent No. 582,605, dated May 11, 1897.

Application filed October 19, 1895. Serial No. 566,215. (No model.) Patented in England No. 11,331 of 1891 and No. 6,806 of 1892.

To all whom it may concern:

Be it known that I, MORGAN DONNE, manager of the works of North's Type-Writer Manufacturing Company, Limited, a subject of the Queen of Great Britain, residing at 57^D, Hatton Garden, London, in the county of Middlesex, England, have invented certain new and useful Improvements in Type-Writing Machines, (for which I have obtained Letters Patent of the United Kingdom No. 11,331 of 1891 and No. 6,806 of 1892,) of which the following is a specification.

The improvements relate more particularly to that class of type-writing machines in which the type-levers are arranged in the arc of a circle facing the operator and in which the printing-point is located between the type-levers and the keyboard, but some parts thereof are also applicable to other forms of type-writing machines; and the objects of the present invention are, first, to provide a simple and efficient means for supporting and guiding the paper-carriage in its movements; secondly, to mount the paper-carriage and couple it with the shifting-bar in such manner that it will be more truly guided and better supported than heretofore, so that there will be no possibility of its springing when in its extreme position and throwing the printing-point out of alinement, while at the same time it will travel more smoothly and with greater steadiness; thirdly, to form and arrange the "hangers" for the type-levers in such manner as to afford broad bearings to the latter; fourthly, to provide a means of readily raising the inking-ribbon guide, together with the inking-ribbon, in order to give an uninterrupted view of the printing when required; fifthly, to provide an efficient means for adjusting or regulating the length of the connecting-rods between the key-levers and the type-levers, and, sixthly, to form the paper-carriage in such manner that it will be lighter, more rigid, and cheaper to produce than heretofore; and in order that the said invention may be clearly understood and readily carried into effect I will proceed, aided by the accompanying drawings, fully to describe the same.

In the drawings, Figure 1 is a transverse section representing a type-writing machine constructed according to the present inven-

tion. Fig. 2 is a similar view of part thereof, drawn to an enlarged scale. Fig. 3 is a side view of a portion of the base of a machine, 55 showing in position the girders which support the paper-carriage. Fig. 4 is a front view thereof. Figs. 5 and 6 are similar views of the base-plate to those last described, but showing the girders removed. Fig. 7 is an 60 inside face view of one of the girders separately. Fig. 8 is a plan thereof. Fig. 9 is an end view thereof. Fig. 10 is an inside face view of the back girder separately. Fig. 11 is a plan thereof. Fig. 12 is a horizontal section of a portion of the paper-carriage. Fig. 13 is a vertical longitudinal section of the shifting bar and adjacent parts. Fig. 14 is a vertical transverse section of part thereof. Fig. 15 is an end view of a portion of the paper-carriage and adjacent parts separately. Fig. 16 is a vertical section taken on the line 1 1 of Fig. 15. Fig. 17 is a horizontal section taken on the line 2 2 of Fig. 15. Fig. 18 is a plan of parts. Fig. 19 is a transverse section 75 taken on the line 3 3 of Fig. 18. Fig. 20 is a plan, partly in section, of a portion of the machine, representing the segmental table and method of mounting the type-levers. Fig. 21 is a front elevation of a portion thereof. Fig. 22 is a side elevation of Fig. 21. Fig. 23 is a side elevation of one of the upper hangers of the upper tier. Fig. 24 is a plan thereof. Fig. 25 is a side elevation of one of the lower hangers of the upper tier. Fig. 26 is a side elevation 85 of one of the upper hangers of the lower tier. Fig. 27 is a plan thereof. Fig. 28 is a side elevation of one of the lower hangers of the lower tier. Fig. 29 is a detached view of parts, showing the device for raising the inking-ribbon. Fig. 30 is a sectional end view 90 representing a modified construction of paper-carriage. Fig. 31 is a section taken longitudinally of the paper-carriage on the line 4 4 of Fig. 30. Fig. 32 is a plan thereof. Fig. 33 is an elevation of one of the end plates separately, and Fig. 34 is a vertical transverse section taken on the line 5 5 of Fig. 33.

In the several figures, in which like parts are indicated by similar letters of reference, 100 Figs. 2, 15 to 28, and 30 to 34 are drawn to an increased scale with respect to the other figures of the drawings.

Referring to Figs. 1 to 29, *a* represents the

base of the machine, which is preferably formed of malleable cast-iron, and which, according to the first part of the present invention, is provided with four vertical lugs or 5 posts a' , which are cast thereon, two being arranged on each side of the base a and each having formed therein a vertical transverse slot or saw-cut a^2 . In connection with these vertical lugs or posts a' two horizontal bars 10 or girders b are employed, which are formed at or near each end thereof with a downwardly-projecting lug b' , adapted to fit the slot a^2 and the vertical post a' , so that both the girders b will extend transversely of the base 15 of the machine and lie parallel to each other, and the girders b are fixed to the vertical posts a' by means of rivets or screws b^2 . These girders b form the supporting means for the paper-carriage hereinafter more fully referred to, and the method of construction 20 above described enables the same to be made more accurately and at less cost than if the girders b were cast in one with the base a , inasmuch as any fitting in connection therewith can be performed prior to fixing the 25 girders b in position upon the base a .

According to the second part of the present invention, c represents the platen-cylinder, which travels with the paper-carriage in 30 the usual way.

c' represents the paper-holder, which is of the well-known skeleton kind, and c^2 represents the scroll or receiver into which the printed paper is received and stored after 35 passing over the platen-cylinder c , and c^3 represents the end plates, which are fixed with the parts hereinbefore described by means of rods or bars c^4 , and which parts constitute the upper carriage.

d represents the transverse bars or girders 40 of the frame of the lower carriage, and d' represents longitudinal bars thereof which are fixed therewith, and these longitudinal bars d' are formed with grooves d^2 therein, arranged 45 longitudinally upon the outer and vertical faces thereof.

The two girders b , which are arranged transversely of the machine, but longitudinally of the carriage at the front and rear 50 thereof, are similarly provided with grooves b^3 upon their inner faces, as shown more particularly at Figs. 1, 2, 3, 7, and 10, and within the grooves b^3 d^2 are fitted two or more hardened-steel balls e , upon which the carriage travels 55 for letter-spacing, stops d^{**} b^{**} being provided at the ends of the grooves b^3 d^2 , in order to prevent the balls e working out of place, as shown more particularly at Fig. 12.

For convenience three balls e are employed, 60 two arranged in the grooves b^3 d^2 at the rear of the paper-carriage, and one located in such grooves at the front of the paper-carriage, as shown more particularly at Fig. 12, but in this latter case the groove b^3 in the girder b 65 at the front of the paper-carriage is formed for a correspondingly short distance in the center thereof, but is of sufficient length to

admit of the proper traverse of the single ball e .

Beneath the lower edge of the grooved bar 70 d' at the front of the paper-carriage, and carried by the corresponding fixed girder b , are arranged, just clear of the lower edge of the grooved bar d' , two rollers b^4 , mounted upon studs or axes b^5 , and the office of these rollers 75 b^4 is, in the event of excessive pressure being brought to bear upon the the paper-carriage, to further assist to support the same and prevent it unduly springing.

In order to support and guide the upper 80 carriage in its to-and-fro movements to shift the printing-point, each end plate c^3 of the upper carriage is at each extremity formed with a horizontal groove or race c^5 , and the end transverse frames or girders d of the 85 lower carriage have fixed therewith, by riveting, short bars of steel d^3 , each formed with a short horizontal groove or race d^4 , corresponding with the grooves c^5 of the end plates c^3 , and hardened-steel balls e are arranged in 90 the recesses or races formed by the grooves c^5 d^4 , so as to admit of the necessary shifting movement of the upper carriage while truly guiding and steadyng the same.

The shifting-lever f —that is to say, the 95 lever moving forward the upper carriage so as to shift the printing-point—usually carries at its upper end a circular rod or shifting-bar which is embraced by a grooved bar resting thereon; but this arrangement gives rise 100 to considerable friction and is therefore objectionable. According to the present invention, however, the grooved bar c^6 , which is fixed with the upper carriage, is still retained, but instead of the circular rod carried by the 105 shifting-lever f a second grooved bar f' or shifting-bar is substituted therefor, as shown more particularly at Figs. 13 and 14, and the two grooved bars, which are internally furnished with stops c^{6*} and f'^* , are so arranged 110 that together they form a race for several balls e , which constitute the connection between the two bars c^6 and f' , and thus the necessary coupling is obtained between the upper carriage and the shifting-bar f with the 115 least possible friction in the traversing of the compound carriage. By this arrangement of parts the paper-carriage is caused to travel with greater facility and truth, and by reason of the greater steadiness with which it is held 120 the printing is much improved.

According to the third part of the present invention, and as shown more particularly at Figs. 20, 21, and 22, the table h for the hangers of the type-levers g , which is segmental in shape, is formed with a step or with two tiers of bearing-surfaces h' h^2 , arranged at different elevations, and the hangers i j are arranged radially side by side theron, as hereinafter more fully described.

The hangers i j , as shown more particularly at Figs. 23 to 28, are formed in the shape of forks at one end spread out to form broad bearings to the shafts or axes g' of the type 130

bars or levers g , and they are at that point formed with cups or recesses $i' j'$, and the ends of the axes g' of the type-levers g are correspondingly cupped to receive hardened-
5 steel balls e , and sensitive antifriction-bearings are thus formed for the type-levers g . The hangers $i j$ are at their opposite ends contracted and held together by bolts or rivets $i^2 j^2$, so as to form apertures $i^3 j^3$ to receive
10 vertical binding-screws $i^* j^*$, which pass through the apertures $i^3 j^3$ and enter corresponding holes formed in the tables $h' h^2$, respectively, combination-washers $i^{**} j^{**}$ being interposed between the heads of the binding-screws $i^* j^*$ and the contracted ends of the
15 hangers $i j$.

In order that the type-levers g may be placed close together, so as to obtain a compact arrangement of the parts and yet have
20 the advantage of the broad bearings, the expanded or bearing ends i' of the hangers i of the upper tier are formed alternately cut away at i^4 upon their upper and under sides, as represented more particularly at Figs. 23
25 and 25, so that they will overlap one another, and thus lie close together at their contracted ends, as shown at Fig. 20.

The hangers j of the lower tier h^2 of the segmental table h are arranged with their expanded or bearing ends j' directed toward the corresponding ends i' of the hangers i of the upper tier, and the contracted ends of alternate hangers j of the lower tier, whose bearings j' for the type-levers, by the overlapping formation of the hangers, are placed at a lower level than those of adjacent hangers, are formed of a reduced height, as represented more particularly at Fig. 28, so as to allow a clear passage for the type-levers
35 g , while the adjacent or overlapping hangers are cut away at j^4 in a similar manner to that described with respect to the upper tier of hangers i and as represented more particularly at Fig. 26, and the contracted ends of
40 the overlapping hangers of the lower tier are preferably reduced, as represented at j^5 in Fig. 26, with a similar object to that described with respect to the reduced height of the lower hanger represented at Fig. 28.

50 According to the fourth part of the present invention, and as represented more particularly at Figs. 1, 2, and 29, a small thumb-lever l is mounted upon an axis of motion l' at the side of the keyboard and is provided with a tail or offset l^2 , which acts upon one end of a lever l^3 , mounted upon an axis of motion l^4 , and at its other end pivotally connected by a link l^5 with an offset l^6 from the ribbon-guide l^7 , which is mounted upon an axis of motion
55 l^8 . By this arrangement of parts when it is desired to raise the ribbon-guide l^7 and inking-ribbon, in order to give a clear and uninterrupted view of the printing, it is only necessary to depress the thumb-lever l , when,
60 through the lever l^3 and link l^5 , the guide l^7 will be raised into a vertical or approximately vertical position, as represented by the dotted

lines in Fig. 29, carrying with it the inking-ribbon, the square end l^{2*} of the offset l^2 of the lever l acting, in conjunction with the corresponding end of the lever l^3 , as a stop to retain the parts with the ribbon-guide l^7 in its raised position in order to free the hand of the operator, while upon returning the lever l to its vertical position the parts will resume their
70 normal positions aided by a coiled spring l^9 , connected with the link l^5 and a fixed part of the machine. The operator can also, by partially raising the ribbon-guide l^7 , obtain a
75 momentary glance at the writing at the printing-point during the progress of the work, in order to satisfy himself of the correctness of the last few letters printed.

According to the fifth part of the present invention, in order to adjust and regulate the
80 length of the connecting-rods between the key-levers and the type-levers, the type-levers g at their upper ends normally rest against a padded shield g^{**} , arranged in the arc of a circle, as is well understood, while at their
85 lower or cranked ends they are pivotally connected at g' with the upper ends of connecting-rods g^2 , the lower ends of which are tapped with a screw-thread g^3 .

Upon the inner end of each key-lever k is
90 pivotally mounted at g^4 a link g^5 , which is drilled with a plain vertical hole g^6 from the upper end downward for a considerable distance, as indicated by the dotted lines in Fig.
95 22, so as to loosely receive the lower tapped
100 ends g^3 of one of the connecting-rods g^2 , while a slot g^7 is formed in the link g^5 , intersecting the vertical hole g^6 , and in which works a many-sided or milled nut g^8 , which engages the threaded end g^3 of the connecting-rod g^2
105 and provides the necessary adjustment between the type-levers g and key-levers k , while at the same time the rigidity of the connection between the key-levers and type-levers is insured.

110 As a further security against accidental movement of the parts a jam-nut g^9 is employed, which works upon the threaded end g^3 of the connecting-rod g^2 and takes an abutment against the upper end of the link g^5 .

115 According to the sixth part of the present invention, and as represented more particularly at Figs. 30 to 34, the transverse bars d of the lower carriage, in lieu of being formed of solid metal, as hereinbefore shown and described, are according to this modification formed of sheet metal stamped into a trough shape, as represented more particularly at Figs. 30, 31, and 32, or such bars might be of **M**-section, as hereinafter described, with
120 respect to the longitudinal bars d' , or they might be of other suitable hollow section adapted to be stamped to the required shape, by which means a bar of great stiffness is obtained at a nominal cost. In the same manner the end plates c^3 of the upper carriage are formed of comparatively light metal stamped into a dished or corrugated form in
125 transverse section, as represented more par-

ticularly at Figs. 33 and 34, or they might be of other suitable hollow section, as will be readily understood.

The longitudinal bars d' of the lower carriage, as represented more particularly at Fig. 30, are formed of an M-section, or they might be of other suitable hollow section, so as to form the grooves d^2 therein, and the longitudinal bars d' are fixed with the transverse bars d by means of angle brackets d^3 and screws or rivets, as shown more particularly at Figs. 31 and 32.

In order to support and guide the upper carriage in its to-and-fro movements to shift the printing-point, each end plate c^3 of the upper carriage has at each extremity fixed thereto by riveting a short horizontally-grooved bar of steel c^5 in lieu of the aperture c , hereinbefore shown and described with respect to Figs. 15, 16, and 17, and the end transverse girders d have riveted thereto corresponding grooved bars d^3 , similar to those shown and described with respect to Figs. 15, 16, and 17.

25 By the arrangement of parts lastly hereinbefore described the construction of the carriage is much cheapened, and it is rendered more rigid and reliable and of less dead-weight than heretofore.

30 Having now particularly described and ascertained the nature of the said invention and in what manner the same is to be performed, I declare that what I claim is—

1. A type-writing machine comprising a support for the paper-carriage consisting of girders formed with lugs thereon in combination with a base formed with posts thereon slotted to receive the lugs of the girders substantially as herein shown and described and 40 for the purpose stated.

2. A type-writing machine comprising an upper carriage having end plates formed at their extremities with horizontal grooves, the lower carriage having longitudinal bars 45 formed with longitudinal grooves upon their outer vertical faces, and transverse bars, the girders arranged transversely of the machine and longitudinally of the carriages, having longitudinal grooves upon their inner vertical faces, the stops located at the ends of the longitudinal grooves, the two balls located in the rear longitudinal grooves, and the single ball located in the front longitudinal grooves, the short bars having horizontal grooves and secured to the end transverse bars of the lower carriage corresponding with the grooves in the end plates of the upper carriage, and the balls located in the horizontal grooves; substantially as described.

60 3. A type-writing machine comprising an upper carriage, the lower carriage having longitudinal bars formed with longitudinal grooves upon their outer vertical faces, the girders arranged transversely of the machine and longitudinally of the carriages, having longitudinal grooves upon their inner vertical

faces, the stops located at the ends of the longitudinal grooves, the two balls located in the rear longitudinal grooves, the single ball located in the front longitudinal grooves, the 70 studs secured to the front girder and the rollers mounted upon the studs just beneath the front bar of the lower carriage; substantially as described.

4. A type-writing machine comprising an upper carriage having end plates formed at their extremities with horizontal grooves, the lower carriage having transverse bars, the short bars having horizontal grooves and secured to the end transverse bars of the lower carriage corresponding with the grooves in the end plates of the upper carriage, the balls located in the horizontal grooves, the grooved bar fixed to the upper carriage, the shifting-lever, the grooved bar fixed to the shifting-lever, the stops secured to the grooved bars and the balls located in the grooved bars; substantially as described.

5. A type-writing machine comprising a table having two horizontal bearing-surfaces 90 arranged at different elevations, the upper tier of forked hangers cut away at their upper and lower sides alternately, the lower tier of forked hangers having their bearing ends directed toward the bearing ends of the upper tier, the alternate hangers of the lower tier being cut away at their inner lower sides, and the intermediate hangers of the lower tier being reduced in height, and the type-levers having extended bearings; substantially as 100 described.

6. The combination, with the type-levers formed with cranked ends, the key-levers, and the connecting-rods formed with threaded ends; of links bored to loosely receive such 105 threaded ends, and formed with slots therein intersecting such bore, nuts working in the slots and upon the threaded ends of the connecting-rods, and jam-nuts also working upon such threaded ends and abutting upon the ends of the links substantially as herein shown and described and for the purpose stated.

7. A type-writing machine comprising a ribbon-guide pivoted to the table, the thumb-lever having an offset, the lever having an end 115 on which the offset of the thumb-lever operates, the link connecting the ribbon-guide to the lever, and the spring for holding the ribbon-guide in normal position; substantially as described.

8. A type-writing machine comprising a paper-carriage mounted upon ball-bearings and provided with auxiliary supporting-rollers normally held clear of the carriage, but adapted to afford a bearing thereto upon the 125 exercise of undue pressure substantially as herein shown and described and for the purpose stated.

MORGAN DONNE.
